SAFETY AUTOMOBILE HEADLIGHT LENS SHIELD

Edward L. Wood, Detroit, Mich.

Application October 17, 1950, Serial No. 12,604

Term of patent 14 years

(Cl. D48—32)

To all whom it may concern:

Be it known that I, Edward L. Wood, a citizen of the United States, residing at Detroit, in the county of Wayne and State of Michigan, have invented a new, original, and ornamental design for a Safety Automobile Headlight Lens Shield, of which the following is a specification, reference being had to the accompanying drawing, forming a part thereof, in which:

Fig. 1 is a view in perspective of a safety automobile headlight lens shield showing my new design;

Fig. 2 is a front elevational view;

Fig. 3 is a top plan view;

Fig. 4 is a side elevational view; and

Fig. 5 is a vertical sectional view taken on the line 5—5 of Fig. 2.

The dot and dash lines in Fig. 1 which indicate

an automobile headlight with which the safety automobile headlight lens shield embodying the invention is used are for illustrative purposes only.

I claim:

The ornamental design for a safety automobile headlight lens shield, substantially as shown and described.

EDWARD L. WOOD.
